UNITED STATES'PATENT OFFICE.

ELBERON D. SMITH, OF BROOKLYN, NEW YORK, ASSIGNOR TO AMERICAN MACHINE & FOUNDRY COMPANY, OF NEW YORK, N. Y., A CORPORATION OF NEW JERSEY.

CIGARETTE-PACKING MACHINE.

1,114,053.

Specification of Letters Patent. Patented Oct. 20, 1914.

Application filed May 20, 1913. Serial No. 768,806.

To all whom it may concern:

Be it known that I, ELBERON D. SMITH, a citizen of the United States, residing at Brooklyn, county of Kings, and State of New York, have invented a new and useful Improvement in Cigarette-Packing Machines, of which the following is a specification.

This invention relates to improvements in machines for packing cigarettes, particularly those in which a plurality of cigarettes is inclosed in a folded sheet of wrapping material, and then inserted in a pouch.

Machines for packing cigarettes have been heretofore used in which cigarettes were inclosed in a folded sheet of wrapping material, but in such machines a group of cigarettes was compressed after the sheet of wrapping material had been partially folded about it, and this operation resulted in creasing or wrinkling the wrapping material so that an unsightly package was produced. Moreover, such packages, owing to the creasing or wrinkling of the wrapping material, are liable to open up and become deformed after the operation of folding the wrapping material about the cigarettes has been completed.

It is one of the objects of the present invention to produce a machine in which a plurality of cigarettes is separated and forwarded from a source of cigarette supply and exposed for inspection so that defective cigarettes may be removed and replaced by perfect cigarettes before any wrapping operation takes place.

Another object is to produce a machine in which a plurality of cigarettes is forwarded from a source of cigarette supply and is then removed from the forwarding means and collocatively compressed and returned to the forwarding means, after which a sheet of wrapping material is folded around the collocation of cigarettes and left in smooth unwrinkled condition.

Still another object is the production of a machine of the character indicated in which the sheet of wrapping material is forwarded by the forwarding means with a plurality of cigarettes resting thereupon, no folding action taking place until after the cigarettes have been removed from the forwarding means, collocatively compressed and returned to the forwarding means.

Still another object is the production of a

machine of this character in which the wrapped collocation of cigarettes is inserted in a pouch.

With these and other objects not specifically mentioned in view, the invention consists in certain constructions, combinations, improvements and parts which will be hereinafter fully described and then specifically set forth in the claims hereunto appended.

In the accompanying drawings, which form a part of this specification and in which like characters of reference indicate the same or like parts, Figure 1 is a side elevation of a machine constructed in accordance with the invention, certain parts being broken away. Fig. 2 is a plan view of the structure shown in Fig. 1, the upper part of the mechanism shown in Fig. 1 being removed. Fig. 3 is a detail side elevation of means employed for feeding a strip of wrapping material and cutting sheets therefrom taken on the line 3—3 in Fig. 2. Fig. 4 is a detail view of a form of brake used in certain parts of the machine illustrated in Figs. 1 to 3 inclusive for preventing overthrow or excessive movement of certain moving parts of the machine. Fig. 5 is a side elevation of the structure shown in Fig. 3 taken on the line 5—5 in Fig. 2. Fig. 6 is a detail plan view showing the mechanism for supporting a reel which in turn supports a strip of wrapping material. Fig. 7 is a detail view, partly in section, showing the source of cigarette supply and the mechanism for separating from said source of supply a definite number of cigarettes. Fig. 8 is a side elevation of the structure shown in Fig. 7 taken on the line 8 in Fig. 1. Fig. 9 is a sectional view taken on the line 9—9 in Fig. 8. Figs. 10 and 11 are respectively fragmentary detail views of one of the pockets carried by the forwarding means for advancing cigarettes. Fig. 12 is a detail view illustrating the mechanism for removing a plurality of cigarettes from the forwarding means into the means for collocatively compressing said cigarettes. Fig. 13 is a plan view of the structure shown in Fig. 12 with operating parts added. Fig. 14 is a front elevation of a portion of the mechanism for folding the sheet of wrapping material around the collocation of cigarettes while in the forwarding means. Figs. 15 and 16 are respectively side and rear elevation of the mechanism for transferring

a collocation of cigarettes from the forwarding means or turret to the means for inserting the wrapped cigarettes in a pouch, Fig. 15 being taken on the line 15—15 in Fig. 2 and Fig. 16 being taken on the line 16—16 in Fig. 15. Fig. 17 is a rear elevation of the device for inserting wrapped cigarettes in a pouch. Fig. 18 is a plan view of a portion of the structure shown in Fig. 17 taken on the line 18—18 in that figure. Figs. 19 to 33 inclusive are diagrammatic views illustrating various operations performed by the mechanism of the machine.

In carrying the invention into effect, there is provided means for forwarding a plurality of cigarettes and means in the path of movement of the forwarding means for removing said cigarettes from the forwarding means and for collocatively compressing said cigarettes while so removed and for replacing them in the forwarding means. In the best constructions, there is further provided a source of cigarette supply, means of separating from the source of supply a definite number of cigarettes, means for collectively forwarding the cigarettes so separated to the compressing mechanism, means for folding a sheet of wrapping material around the compressed cigarettes, and means for thereafter inserting the wrapped cigarettes in a pouch. In the best constructions also, the forwarding means will be given a step-by-step movement and the other mechanisms will be operative only while the forwarding means is at rest. In the best constructions also, there is provided means for supporting a strip of wrapping material and means for severing from said strip a sheet of wrapping material, which is advanced by the forwarding means with a plurality of cigarettes resting thereupon, but is not folded around said cigarettes until after the latter have been collocatively compressed. All of the elements above enumerated may be varied in construction within wide limits. The machine selected to illustrate the invention is but one of many possible concrete embodiments of the invention, and it is therefore to be understood that the invention is not to be restricted to the precise details of the structure shown and described.

In the machine selected to illustrate the invention, 1 indicates the main frame of the machine built up in a manner well known to mechanics generally, and a detailed description thereof is therefore omitted in the interest of brevity. The main frame 1 supports a power shaft carrying a friction pulley 2 (see Fig. 1) and a hand wheel 3, by means of which the machine may be turned over by hand for adjusting or other purposes. The main power shaft carries a pinion 4 which is in mesh with a spur gear 5 fast upon a shaft 6 jour-

naled in brackets 7 rising from the main frame of the machine. The shaft 6 carries a bevel gear 8 which is in mesh with a similar bevel gear 9 fast upon a vertical shaft 10 journaled in bearings in the main frame. The lower end of the shaft 10 carries a bevel gear 11 which is in mesh with a bevel gear 12 fast upon a shaft 13 which shaft is journaled in suitable bearings formed in the main frame. The shaft 13 carries a bevel gear 14 which is in mesh with another bevel gear 15 carried by a shaft 16 journaled in brackets 17 secured to the main frame of the machine (see Fig. 2). The shafts and gearing just described constitute the main driving elements of the machine.

There is provided a source of wrapping material supply which includes a reel for supporting a strip of wrapping material wound thereupon. The reel includes a shaft 18 (see Figs. 2, 3, 5 and 6), upon which is pinned a flange 19, and upon which is secured a flange 20. One end of the shaft 18 is reduced at 21 and the reduced end engages a collar 22, which collar is adjustable in the direction of the axis of the shaft 18 through the agency of a screw 23 and operating handle 24 of well-known construction. The purpose of this adjustment is to insure the proper alinement of the strip of wrapping material with the devices to which it is fed. The shaft 18, at a point adjacent the flange 19 carries an arm 25 adjustably clamped thereupon. This arm contacts with a bent lever 26 (see Fig. 3). The bent lever is fulcrumed at 27 to a bracket 28 extending to the left from the main bracket 29 which supports the shaft 18. The free end of the lever 26 is hooked to one end of a spring 30; the other end of the spring is hooked on a post 31 secured to the main frame of the machine. The extreme end of the shaft 18 opposite the operating wheel 24 rests in an open bearing 32. It will be readily understood that during the operation of the machine an exhausted reel may be lifted from its bearings and replaced by a full reel without disconnecting any of the parts heretofore described. It may be here remarked that two such reels are supplied with each machine so that while one is in use, the other may have a strip of wrapping material wound upon it through some outside agency. The strip of wrapping material is led from the reel over a guide pulley 33 on a shaft 34, which shaft is journaled in the main frame of the machine. From the guide pulley 33 the strip of wrapping material passes over a table 35 into the range of action of a pair of feed rollers 36—37. The feed roller 36 is fast upon a shaft 38 journaled in the main frame of the machine. This shaft 38 carries a spur gear 39 which is in mesh with

an idle gear 40 loosely mounted upon a stud 41 secured to the main frame of the machine. The idle gear 40 is in mesh with a spur gear 42 loosely mounted upon a shaft 43, which shaft is journaled in suitable bearings in the main frame of the machine and which carries a spur gear 44 in mesh with a spur gear 45, the latter being fast upon the shaft 16 before referred to. The spur gear 39 is also in mesh with a spur gear 46, the spur gear 46 being fast upon a shaft 47, which carries the feed roller 37 before referred to. The shaft 47 is journaled in boxes 48, which boxes are spring pressed and slidably mounted in a well-known manner in uprights rising from the main frame of the machine. The hub of the spur gear 42 is provided with a ratchet 49, which ratchet 20 is engaged by a pawl 50 mounted upon the lever 51, the lever being loosely mounted upon the shaft 43 adjacent the ratchet 49. The lever 51 is connected by means of a link 52 to a cam lever 53, which cam lever 25 is fulcrumed at 54 to the main frame of the machine. The cam lever 53 carries a bowl 55 engaging a slot in a cam disk 56 fast upon the shaft 43 before referred to.

It will be readily understood that the 30 mechanism just described operates to intermittently rotate the feed rollers 36 and 37 and thereby produce an intermittent feeding movement of the strip of wrapping material. From the feed rollers 36 and 37 the strip of wrapping material passes over a table 57 and under a removable plate 58 to a shearing device operated to sever a sheet of wrapping material from the strip. This shearing device consists of a fixed plate 59 and an oscillating shear blade 60 which is fulcrumed at 61 to the frame of the machine. The shear blade 60 is connected by means of an adjustable link 62 to a bell-crank lever 63-64. The bell-crank lever is pivoted at 65 to a bracket 66 extending from the frame of the machine. The arm 64 of the bell-crank lever 63-64 carries a bowl 67 running upon the face of the cam 56 before referred to, and it is to be understood 45 that this cam carries a projection timed to swing the shear blade 60 upwardly so that it can coöperate with the fixed blade 59 to cut the strip at the proper time. The bowl 67 is held to its duty by means of a spring 55 68, one end of which is fast to the main frame, and the other end is fast to the upper pivot of the connecting rod 62.

Before the cut is effected, the strip of 60 wrapping material is projected by the feed rollers 36-37 beyond the shearing position and over the top of a pocket 69 in which cigarettes are afterward deposited.

Overthrow or excess movement of the 65 ratchet operated spur gear 42 is prevented by a brake mechanism illustrated in Fig. 4.

This brake mechanism includes an arm 70 having an elongated head in which is mounted a plunger 71, a spring 72 engaging said plunger, and a plug 73 for regulating the tension of the spring. The arm 70 is clamped at 74 to the main frame and the plunger end bears against the gear 42. Similar plunger brakes are applied to the feed rollers 36 and 37 at 75 and 76 respectively.

In the machine selected to illustrate the invention a plurality of cigarettes is placed upon the sheet of wrapping material which has been severed from the strip and is forwarded while resting upon said sheet of wrapping material. The cigarettes are placed upon the sheet of wrapping material automatically and to this end there is provided a source of cigarette supply which includes a hopper 77 for containing cigarettes in bulk. The bottom of the hopper is formed by a belt 78 running over pulleys 79-80. The pulley 79 is mounted upon a shaft 81 which carries a sprocket 82 over which runs a chain 83. The chain 83 runs over a sprocket 84 journaled upon the shaft 43 before referred to. The hub of this sprocket carries a ratchet 85 which is engaged by a spring pressed pawl 86 carried by the hub 87 of the gear 44 before referred to. In a normal operation of the machine 90 the gear 44 continuously rotates and through the connections just described the belt 78 forming the bottom of the hopper 77 is also continuously operated. The function of the pawl and ratchet mechanism 85-86 is to 95 permit of the belt 78 being operated temporarily by hand for the purpose of feeding down cigarettes at the beginning of a machine run. There is also provided within the hopper 77 an agitating wheel 88 of well-known construction which is driven by a belt 89 from a pulley 90 fast on the shaft of the pulley 80 over which the feed belt 78 runs. The belt 78 and agitator 88 co-operates to dispose cigarettes in a line upon the belt, and the belt 78 operates to feed this line of cigarettes forward into an inclined chute 91, which leads downwardly to a point adjacent the pocket 69 and immediately over the sheet of wrapping material fed forward to and over the pocket by the feed rollers 36 and 37 before described. The general construction of this cigarette feeding mechanism is old and well known in the art and a more detailed description thereof is omitted in the interest of brevity. It may be here remarked, however, that the cigarettes fall by gravity through the chute 91, the weight of the column of cigarettes being sufficient to drive a definite number across the pocket 69 into position to be rammed down into said pocket. The pocket 69 in the machine shown is one of eight like pockets symmetrically arranged around the periphery 115 of a turret 92. This turret 92 is mounted 120

upon a shaft 93 suitably supported in a vertical bearing formed on the machine frame, and the turret is rotated by means of an arm 94 mounted upon the shaft 10 before referred to. This arm carries a bowl 95 engaging slots 96 formed in the under side of the turret. This mechanism constitutes what is known as a Geneva movement, which needs no further description.

10 The turret pockets are all alike and therefore a description of one will serve as a description of all. Referring particularly to Figs. 10 and 11: Each pocket, generally indicated by the reference character 69, includes a rectangular casing 97, open at the top and at both sides and having a movable bottom. When, as in the case of the machine selected to illustrate the invention, twenty cigarettes are to be placed in each 20 package, two rows of seven and one row of six, the movable bottom of each turret pocket is constructed of two plates numbered respectively 98 and 99. The plate 98 is fixed upon the upper end of a plunger 100, and the plate 99 is fixed upon the upper end of a plunger 101. These plungers are slidably mounted in a block 102 closing the lower part of the casing 97 below the movable plates 98 and 99. Spring pressed 30 plunger brakes of the type shown in Fig. 4 are employed for the purpose of holding the plungers 100 and 101 in any position to which they may be moved. These plunger brakes are indicated in Figs. 10 and 11 by 35 the reference characters 103 and 104, the brake 103 coöperating with the plunger 100 and the brake 104 coöperating with the plunger 101. For the purpose of retaining cigarettes placed in the pocket in longitudinal alinement, there are provided swinging gates 105 fulcrumed at 106 to bosses 107 extending from the sides of the casing 97 before referred to. These gates carry fingers 108 at their upper ends, the free 45 ends of which contact with and aline cigarettes resting upon the plates 98 and 99 within the casing 97. During the operation of the machine, these gates are held open a part of the time, and closed a part of the 50 time. To so hold them, each gate is provided with a stud 109 which engages one end of a toggle lever 110. The other end of the toggle lever engages a spring pressed block 111 suitably mounted in the block 102 55 before referred to. This stud, toggle lever and block constitute a toggle mechanism which automatically operates to hold the gate either in open or closed position in a well-known manner. Each of the gates is 60 further provided with a stud 112 projecting beyond the periphery of the turret 92. In the position in which the pocket receives cigarettes, the gates lie in open position; that is, the position shown in broken lines 65 in Fig. 11. As soon as the cigarettes are de-

posited in the pocket, the gates are closed. This result is effected by means of a yoke formed on the upper end of a bar 113 (see Figs. 3, 10 and 11), which is slidably mounted in a bracket 114 secured to the 70 main frame of the machine. The lower end of the bar 113 is pivotally connected with an adjustable link 115, which in turn is pivotally connected to a cam lever 116 mounted upon the bar 117 extending across 75 the machine. The cam lever 116 carries a bowl 118 which tracks upon the periphery of a cam 119, which cam is fast upon the shaft 13 before referred to. One end of a spring 120 is secured to the bracket 114 and 80 the other end is secured upon a stud 121 fast to the link 115. This spring operates to hold the bowl 118 against the periphery of the cam 119 and it is to be understood that the cam is shaped to permit the spring 85 to act to push the bar 113 and its yoke upward immediately after the required number of cigarettes has been placed in the pocket; and it is further to be understood that immediately after this action takes 90 place, the cam again returns the yoke and its connections to its normal position or that shown in Fig. 3.

When cigarettes are to be placed in the pocket, the plates 98 and 99 occupy the position in which they are shown in Fig. 3, and it is to be understood that they are held in this position by means of the brake plungers 103 and 104 before referred to.

Cigarettes descending the chute 91 are not 100 delivered directly to the pocket, but are delivered to a counting mechanism or mechanism for separating from the source of supply a definite number of cigarettes and from this mechanism they are transferred to the 105 pocket. The mechanism referred to includes a bracket 122 (see Figs. 7, 8 and 9) depending from the main frame of the machine. This bracket has two bosses 123—124, in which is mounted a plunger 125. The lower 110 end of this plunger carries a plunger head 126 normally occupying the position shown in Fig. 7. Between the bearings 123 and 124 there is mounted an arm 127 fast to the plunger. The free end of this arm engages a spring 128, the free end of which projects into the chute 91 and holds up a portion of the cigarettes in the chute for the purpose of preventing too great a pressure upon the lowermost cigarettes lying in the 115 chute. Coiled around the plunger 125 is a spring 129 which bears against the bearing 124 and the arm 127. The function of this spring is to hold the plunger and arm in its uppermost position, or that shown in Fig. 7. The upper end of the plunger is pivotally connected with an adjustable link 130, which in turn is pivoted to a cam lever 130. The cam lever 130 is loosely mounted upon a bar 131 suitably supported in the bracket 122 125 130

before referred to. The cam lever 130 carries a bowl 132 engaging a cam groove 133 formed in a cam disk 134 fast on the shaft 6 before referred to. Immediately to the 5 left of the plunger head 126 is a narrow head 135 formed on a plunger bar 136 mounted to slide in a bracket 137 adjustably mounted on the bracket 122 before referred to. The lower side of the plunger 10 head 135 normally lies in the same plane as the lower side of the plunger head 126. The upper end of the plunger bar 136 is pivotally connected with a link 138 which in turn is pivotally connected to a bell-crank 15 cam lever 139 fulcrumed on the bar 131 before referred to. The bell-crank lever 139 carries a bowl 140 tracking on the periphery of a cam 141 fast on the shaft 6 before referred to.

20 The lower end of the bracket 122 carries an adjustable abutment 142 by means of which the number of cigarettes which can pass under the plunger heads 126 and 135 is determined. The lower end of the bracket 25 122 further carries two swinging gates 143 normally held in the positions shown in Figs. 8 and 9 by means of sensitive coiled springs 144 coiled around the pintles 145, upon which these gates are pivoted. The 30 gates 143 are separated a sufficient distance to permit the cigarettes to pass along their upper surface and under the plunger heads 126 and 135. In the machine selected to illustrate the invention, when seven cigarettes 35 have been projected along the gates 143 which support their ends, the cams 134 and 141 operate to move the plunger heads 126 and 135 downward into the pocket. During 40 this action the cigarettes operate, first to open the gates 143 against the action of their sensitive springs and then to push the pocket plates 98 and 99 downward against the action of their respective brake plungers. The plunger heads 126 and 135 then return 45 to their normal position and another line of cigarettes passes on the gates 143. The cams 134 and 141 then operate a second time to push the second line of cigarettes down into the pocket, which, of course, depresses the 50 pocket plates 98 and 99 still more. After the second line of cigarettes has been deposited in the pocket, the plunger head 135 remains in its low position, but the plunger head 126 returns to its normal position. A 55 third line of six cigarettes only is then projected by the weight of the cigarettes in the chute 91 on the gates 143. The cam 134 then operates to push the plunger head 126 downward, thus forcing the third line of six cigarettes 60 down upon the two lines of seven previously placed in the pocket. Both plunger heads are then returned to normal position and clear of the pocket so that the turret may be rotated to forward the cigarettes lying 65 in the pocket.

The operation of that part of the machine just described is clearly illustrated in Figs. 19 to 22 inclusive. In Fig. 19, one line of seven cigarettes has been projected by gravity into position for insertion in one of the 70 pockets 69. In Fig. 20, this first line of seven cigarettes has been deposited in the pocket and the plungers 126 and 135 have been returned to their normal position and a second line of seven cigarettes has been projected into position to be inserted in the 75 pocket. In Fig. 21, the second line of cigarettes has been deposited in the pocket and the plunger 126 has been returned to its normal position, while the plunger 135 has been 80 only partially retracted so that only six cigarettes can be projected into position for insertion in the pocket. Fig. 22 illustrates the action of the gates after the full twenty cigarettes have been inserted in the pocket, 85 the gates being swung up into position for alining the cigarettes endwise.

It may sometimes happen that there are not enough cigarettes in the chute 91 to fill a pocket and in such case, the pocket plates 90 98 and 99 would not be pushed down to their lowermost position. To prevent breakage of parts in such case, the plunger bar 136 carries a yoke 146 provided with two pins 147, the function of these pins being to push 95 the pocket plate down to its lowermost position only when the pocket is not filled with cigarettes.

As soon as the full number of cigarettes has been deposited in a pocket adjacent the 100 source of cigarette supply, the turret 92 is given a movement which brings the pocket into the position indicated at IP in Fig. 2. In this position the cigarettes are exposed for inspection and if the pocket 105 contains a defective cigarette, the operator removes the same and replaces it by a perfect cigarette. From this position the turret is again given a movement which brings the pocket into the position indicated at 110 2 IP in Fig. 2, the second inspection position, where it again comes to rest. It is obvious that the operator may remove defective cigarettes and substitute perfect ones in either of these two inspection positions, 115 or may remove the defective cigarettes in the first inspection and substitute a perfect cigarette in the second inspection position. From the second inspection position the pocket is carried by a further movement 120 of the turret to a compressing position indicated at CP in Fig. 2. When any pocket containing the required number of cigarettes reaches the compressing position, the cigarettes are removed from the pocket, 125 collectively compressed and then returned to the pocket. In the device selected to illustrate the invention, this operation is accomplished by the following mechanism: Located immediately over a turret pocket, 130

when the same is in the compressing position (see Fig. 12), is a rectangular casing 148 secured to a bracket 149, which bracket is supported from the main frame of the machine. Within this casing is mounted a plate 150 secured to the lower end of a plunger 151. The plate 150 normally occupies the position shown in Fig. 12. The lower part of the inner side wall of the rectangular casing 148 is cut away and in the opening thus formed is located a plunger or movable wall 152 carried by a slide 153 mounted in ways 153' secured to the bracket 149. This plunger 152 normally occupies the position shown in Fig. 12. Before the cigarettes can be removed from the pocket 69, the swinging gates 105 are opened or thrown back out of contact with the ends of the cigarettes. This movement is effected by the following mechanism: Located adjacent the periphery of the turret 92 at the compressing position is a yoke 154 having ledges 155 which normally overlie the path of movement of the studs 112 secured to the gates 105. As the turret rotates, these studs pass under the ledges 155. The yoke 154 is secured to a slide 156 mounted in a bracket 157 secured to the main frame of the machine. The slide 156 is connected by means of a link 158 with a cam lever 159. This cam lever is fulcrumed on the bar 117 before referred to (see Fig. 1). This cam lever carries a bowl 160 tracking on the periphery of a cam 161 fast on the shaft 13 before referred to. The cam 161 is shaped to produce a downward movement of the yoke 154 immediately after a pocket containing the required number of cigarettes reaches the compressing position; and a spring 162, which connects the cam lever 159 with the bracket 157, operates to hold the bowl 160 to its duty and to return the yoke 154 to its normal position. After the gates have been opened, the cigarettes are to be removed from the pocket and compressed. The bracket 157 has bearings 163 and 164, through which respectively work plungers 165 and 166. The plunger 165 is connected by means of a link 167 to a cam lever 168 fulcrumed on the bar 117 before referred to. The lever 168 carries a bowl 169 tracking in a groove 170 formed in a cam wheel 171 which is fast on the shaft 13. Similarly, the plunger 166 is connected by means of a short link 172 to a cam lever 173 also fulcrumed on the bar 117. The cam lever 173 carries a bowl 174 tracking in a suitable groove in the side of the cam wheel 171 opposite that carrying the groove 170. The upper end of the plunger 165 lies immediately under the lower end of the plunger 100 of the pocket only when the latter is in compressing position. Similarly, the upper end of the plunger 166 lies immediately below the

lower end of the plunger 101 of the pocket only when the latter is in compressing position. The cam 171 produces a simultaneous upward movement of the plungers 165 and 166 which in turn produces a simultaneous upward movement of the pocket plungers 100 and 101. This action is clearly shown in Fig. 23, which diagrammatically illustrates the transferring or removing action. In Fig. 23, however, the plungers 100 and 101 have not reached the extreme upper limit of their movement. This extreme upper limit of their movement is shown in Fig. 24. By reference to Figs. 23 and 24, it will be readily seen that as the cigarettes are removed from the pocket, the sheet of wrapping material upon which they rest is straightened out. As soon as the plungers 100 and 101 reach their uppermost position, the plunger 152 is moved inwardly, as is clearly shown in Fig. 24. This movement is produced by the following mechanism: The slide 153 is connected by means of a link 175 to an arm 176 fixed upon the lower end of a short shaft 177. This shaft is journaled in suitable bearings in the bracket 149 before referred to. The upper end of the shaft carries an arm 178, the free end of which carries a bowl 179 tracking on the side of a cam 180 fixed upon the shaft 6 before referred to. The cam 180 is shaped to move the plunger 152 from the position shown in Fig. 23 to the position shown in Fig. 24, and to hold it there until the plate 150 carried by the plunger 151 has finished its operation. The plunger 151 is pivoted to a cam lever 181 (see Fig. 13), which is fulcrumed on the stud 182 suitably supported in the bracket 149. The lever 181 carries a bowl 183 tracking on the periphery of the cam 180 before referred to. As soon as the cigarettes are compressed sidewise, as shown in Fig. 24, the plunger 151 and the plate 150 move downward, as indicated in Fig. 25, to return the cigarettes now collocatively arranged to the pocket. By an inspection of Figs. 24 and 25, it will be seen that during this action, only the pocket plate 98 is moved downward, the plate 99 remaining in its uppermost position to form the side wall of the pocket now reduced in size.

The plunger 151 carries an arm 184 to which is clamped a pin 185, the function of this pin being to force the plate 98 downward in the event of the machine running without the required number of cigarettes in the pocket.

It is sometimes desired to insert in the package of cigarettes a card or coupon and the machine selected to illustrate the invention is provided with mechanism for performing this function. This mechanism comes into operation while a pocket is in the compressing position and just before the

cigarettes are removed from the pocket to the compressing mechanism. With this end in view, there is provided a table 186 (see Figs. 12 and 13), projecting outwardly from the casing 148 before referred to. Flush with this table is an opening 187 formed in the outer wall of the casing 148. Mounted upon the table 186 is a slide 188 free to move toward and away from the opening 187. This slide carries a stud 189 which is pivoted to a link 190. This link is also pivoted to a cam lever 191 fulcrumed at 192 to a bracket 193 supported by the bracket 157 before referred to. The cam lever 192 carries a bowl 194 running on a cam plate 195 screwed to the slide 156 before referred to. It will be readily understood that as the slide 156 is moved upward it operates the cam lever 191 and the slide 188 to push a coupon or card lying on the table 186 through the opening 187 to the interior of the casing 148, as is clearly shown in Fig. 23. For the purpose of returning the slide 188 to its normal position, or that shown in Fig. 12, there is provided a spring 196, one end of which is fast to the lever 191 and the other end to the bracket 157.

After the cigarettes have been collocatively compressed and returned to the turret pocket, with or without a card or coupon lying thereupon, the turret is given another movement which brings the cigarettes and the sheet of wrapping material into position for folding the sheet of wrapping material around the cigarettes. While the cigarettes in the pocket are moving from the compressing position to the first folding position, they pass under a plate 197 which is fast upon an arm 198 fulcrumed at 199 on a vertical shaft 200, which shaft is mounted in suitable bearings formed in a bracket 201 secured to the main frame of the machine. The upper end of the shaft 200 is provided with an arm 202 carrying a stud 203 which engages a slot in one end of a cam lever 204. This cam lever is fulcrumed on a stud 205 suitably mounted in the bracket 201. The other end of the lever 204 carries a bowl 205 tracking on the side of a cam 206 fast on the shaft 6 before referred to. A spring 207 is provided, one end of which is hooked over a stud 208 carried by the cam lever 204; and the other end of the spring is secured to a fixed post, not shown but mounted on the main frame of the machine. This spring serves to keep the bowl 205 in contact with the cam 206 and to cause the plate 197 to travel with the pocket containing the collocatively compressed cigarettes to the first folding position. This cam 206 is so formed as to return the plate 197 to its normal position, or that shown in Fig. 13, at the proper time.

The mechanism for making the first folds of the sheet of wrapping material

about the collocated cigarettes is illustrated in Figs. 1, 13 and 14. As the cigarettes come to the first folding position, they and the sheet of wrapping material lie in the position shown in Fig. 14. The inner flap 70 is first folded over the cigarette. This is accomplished by means of a folding plate 209 fast upon a slide 210 mounted in ways carried by the main frame of the machine immediately over the turret. The slide is pivotally connected by means of a link 211 to a cam lever 212 fulcrumed at 213 on a stud 214 suitably supported in the frame of the machine. The other end of the lever 212 carries a bowl 214 tracking in a groove 215 formed in the periphery of a cam drum 216 fast on the shaft 6 before referred to. This groove is shaped to produce a movement of the slide 210 and folding plate 209 across the pocket before the plate 197 is returned 85 to its normal position. This movement folds one side of the sheet of wrapping material over the top of the cigarettes lying in the pocket. The slide 210 further carries folding plates 217 which fold in the inner 90 ends of the wrapping material as shown diagrammatically in Fig. 26. Opposite the cam plate 209 and beyond the turret 92 is a coöperating folding plate 218 which is carried by a slide 219 suitably supported in 95 ways formed in the main frame of the machine. This slide 219 is connected by means of a link 220 to a cam lever 221 fulcrumed at 222 to a stud supported by the frame of the machine. The lever 221 carries a bowl 100 223 tracking in the cam groove 224 formed in the cam drum 216 before referred to. This slide 219 further carries a folding plate 225 similar in construction and operation to the plates 217 before referred to. 105 As soon as the plate 209 has reached the limit of its movement, as shown in Fig. 26, its operating cam causes it to retreat and the operating cam of the plate 218 then comes into action to cause the plate 128 to 110 follow the plate 209 back across the pocket, as shown in Fig. 27. This results in overlapping the two sides of the sheet of wrapping material on the top of the cigarettes in the pocket and in folding the ends in. At 115 this time the swinging gates 105 are again swung up into position to hold the wrapping material in position as folded at the ends of the cigarettes. This is accomplished by means of a slide 226 carrying a 120 yoke 227 which is adapted to engage the studs 112 of the gates and throw the latter into operative position. The slide 226 is mounted in a bracket 228 secured to the main frame of the machine, and its lower 125 end is pivoted to one end of a link 229. The other end of the link 229 is pivoted to a cam lever 230 fulcrumed on the bar 117 before referred to. The cam lever 230 carries a bowl 231 tracking on the periphery of a cam 130

232 fast on the shaft 13 before referred to. The bowl 231 and cam lever 230 are held to their duty by means of a spring, not shown, but similar in all respects to the spring 162 before referred to.

From the position in which the initial folds of the sheet of wrapping material about the cigarettes are made, the partially wrapped cigarettes move to a position where they are ejected from the turret pocket. Between these two positions they pass under a plate 233 (see Fig. 2) secured to an arm 234 which arm is pivoted at 235 to a bracket 236 secured to the main frame of the machine. A spring 237 is coiled around the pindle of the arm 234 and exerts a downward pressure on the same in a well-known manner so that the overlapped folds of the sheet of wrapping material lying above the cigarettes are kept down in place. When the partially wrapped collocation of cigarettes reaches the ejecting position, the pocket plunger 100 comes to a position immediately over a plunger 238 (see Figs. 15 and 16), and the studs 112 of the swinging gates 105 come into engagement with a yoke 239 carried by a slide 240, both the slide 240 and the plunger 238 being mounted in a bracket 241 secured to the main frame of the machine. The slide 240 is connected by means of a link 242 to a cam lever 243 fulcrumed on the bar 117 before referred to. This cam lever 243 carries a bowl engaging a slot in one side of the cam wheel 244. The plunger 238 is connected by means of a link 245 with a cam lever 246 also fulcrumed on the bar 117. The cam lever 246 carries a bowl engaging a groove in the opposite side of the cam wheel 244. It is to be understood that the grooves in this cam wheel are shaped to provide the proper movements for the slide 240 and the plunger 238 at the proper time. The slide 240 is operated first and this throws the swinging gates 105 to open position. The plunger 238 is then operated and this results in pushing the partially wrapped package up out of the pocket. In passing up out of the pocket, the overhanging and overlapped upper parts of the wrapping material are bent downwardly by stationary folding devices 247 and 248, as is clearly indicated in Figs. 29 and 30. Mounted above the pocket at this position is a bar 249 upon which is mounted a slide 250. This slide has a depending fixed wall 251 and a pivoted wall marked 252. Between these two walls is located a plunger 253 the lower end of which terminates in a plate 254 which overlies the partially wrapped collocation of cigarettes. This plunger and plate are normally held in their lowermost position by gravity. The pivoted wall 252 carries an adjustable screw 255 which contacts with a projection 256 formed

on the folding device 248 before referred to. The pivoted wall 252 is further provided with a lateral projection 257, and the spring 258 lies between this projection and the main part of the slide 250. In the position shown in Fig. 15, the pivoted wall 252 is held out slightly so that the distance between it and the wall 251 is slightly greater than the width of the pocket in which the cigarettes lie. When the plunger 100 is moved upward to eject the partially wrapped collocation of cigarettes from the turret pocket, the plate 254 and plunger 253 are lifted. The plate and plunger have, however, sufficient weight to retain the overlapped portions of the wrapping material in smooth position upon the cigarettes.

As soon as the cigarettes are transferred from the turret pocket to a position between the walls 251 and 252, the slide 250 is given a movement to transfer said cigarettes to a position where they are completely wrapped and finally inserted in a pouch. The mechanism for effecting this movement is as follows: The slide 250 has a stud 259 to which is pivoted one end of a link 260. The other end of the link 260 is pivoted to an arm 261 which is loosely mounted upon a stud 262. Underlying the arm 261 is a bell-crank lever 263—264. This bell-crank lever is also loosely mounted upon the stud 262. The arm 264 of the bell-crank lever carries a bowl 265 tracking in a cam groove 266 formed in the cam 206 before referred to. The arm 263 of the bell-crank lever is provided with lateral projections 267—267, one lying on either side of the arm 261. Springs 268—268 are interposed between these lateral projections and the arm 261. The movement of the bell-crank lever is slightly in excess of the movement of the arm 261, the springs 268 taking up this excess movement. This construction is of a well known character and is employed for the purpose of insuring the accurate alinement of the slide 250 with a pocket turret and also with ejecting mechanism whereby the package is inserted in the mouthpiece. In the path of movement of the slide 250 are located stationary bending devices 269 and 270 (see Fig. 30). The bending device 270 turns up that portion of the folded wrapper lying to the right in Fig. 30 into the position shown in Fig. 31, while the bending device 269 bends the unfolded part of the wrapping material down, as shown in Fig. 31. The fold, when completed, is shown clearly in Fig. 33. The upper end of the plunger 253 carries a bowl 271 which tracks on a stationary cam 272. This cam is shaped to hold the plunger in its uppermost position during the transfer of a package and holds it up during the greater part of the return movement, but at the latter part of the re-

turn movement it permits said plunger to fall by gravity to its normal position. When the package has been transferred by the slide 250, it is brought in front of an 5 ejector 273 mounted upon a plunger 274 which is carried by a slide 275 mounted on a bar 276 suitably supported from the main frame of the machine. The slide 275 is pivotally connected by means of a link 277 to 10 a cam lever 278. This cam lever is fulcrumed at 279 to a bracket 280 extended from the main frame of the machine. The cam lever 278 carries a bowl 280' engaging a groove in a cam wheel 281. The cam wheel 15 is fast on the shaft 16 before referred to. The cam groove is arranged to produce a movement of the ejector 273 at the proper time to force the wrapped package through a spout 282 formed of two sections, the 20 lower section being fixed to a bracket 283 suitably supported by the main frame of the machine, and the upper section being pivoted to said bracket at 284. Upon this spout one of the operators of the machine slips a 25 pouch of paper or other suitable material. This pouch is indicated at 285, and the upper section of the spout is provided with a stop against which the pouch abuts. As the ejector moves forward, it pushes the 30 wrapped package into the pouch and the package pushes the pouch from the spout. The pouch containing the package of cigarettes then slides down over a guide plate 287 to a moving belt 288, by means of which it 35 is delivered from the machine. This belt runs over a pulley 289 and a similar pulley not shown but suitably supported by the main frame of the machine in a well known manner. The pulley 289 is fast upon a shaft 40 290 and this shaft 290 carries a spur gear indicated at 291, which spur gear is in mesh with a spur pinion 292 fast on a shaft 293 suitably supported in bearings carried by the main frame of the machine. The shaft 45 293 also carries a sprocket indicated at 294 over which runs a chain indicated at 295. This chain also runs over a sprocket 296 fast on the shaft 16 before referred to.

After a wrapped package has been inserted in a pouch and delivered to the belt 288, the cycle of operations is repeated.

In view of the foregoing, a detailed description of the operation of the device is deemed unnecessary and is therefore omitted 55 in the interest of brevity.

What is claimed is:

1. In a cigarette packing machine, the combination with means having an intermittent movement in one direction only for 60 forwarding a plurality of cigarettes, of means in the path of movement of the forwarding means for removing said cigarettes from the forwarding means and for collocatively compressing said cigarettes while so

removed and for replacing them in the for- 65 warding means.

2. In a cigarette packing machine, the combination with a source of cigarette supply, of means having an intermittent movement in one direction only for forwarding a 70 plurality of cigarettes from said source of supply, and means in the path of movement of the forwarding means for removing said cigarettes 75 from the forwarding means and for collocatively compressing said cigarettes while so removed and for replacing them in the forwarding means.

3. In a cigarette packing machine, the combination with a source of cigarette supply, of means for separating from the source 80 of supply a definite number of cigarettes, means having an intermittent movement in one direction only for collocatively forwarding the cigarettes so separated, and means in the path of movement of the forwarding 85 means for removing said cigarettes from the forwarding means and for collocatively compressing said cigarettes while so removed and for replacing them in the forwarding means.

4. In a cigarette packing machine, the combination with a source of cigarette supply, of means for separating from the source of supply a definite number of cigarettes, means for collocatively forwarding the cigarettes 95 so separated, means in the path of movement of the forwarding means for removing said cigarettes from the forwarding means and for collocatively compressing said cigarettes while so removed and for replacing them in 100 the forwarding means, the removing and compressing means being spaced from the separating means a sufficient distance to enable the operator to remove from the forwarding means any defective cigarette and 105 replace it with a perfect cigarette before the collocation reaches the removing means.

5. In a cigarette packing machine, the combination with means having an intermittent movement in one direction only for forwarding a plurality of cigarettes, of means in the path of movement of the forwarding means for removing said cigarettes from the forwarding means and for collocatively compressing said cigarettes while so removed 110 and for replacing them in the forwarding means, and means for thereafter folding a sheet of wrapping material around the collocation of compressed cigarettes.

6. In a cigarette packing machine, the 115 combination with means having an intermittent movement in one direction only for forwarding a plurality of cigarettes, of means in the path of movement of the forwarding means for removing said cigarettes from the 120 forwarding means and for collocatively compressing said cigarettes while so removed 125 and for replacing them in the forwarding

- means, and means for thereafter folding a sheet of wrapping material around the collocation of compressed cigarettes while said collocation of compressed cigarettes is being advanced by the forwarding means.
7. In a cigarette packing machine, the combination with means having an intermittent movement in one direction only for forwarding a plurality of cigarettes, of means in the path of movement of the forwarding means for removing said cigarettes from the forwarding means and for collocatively compressing said cigarettes while so removed and for replacing them in the forwarding means, means for folding a sheet of wrapping material around the collocation of compressed cigarettes, and means for inserting the wrapped collocation of cigarettes in a pouch.
- 10 8. In a cigarette packing machine, the combination with a source of cigarette supply, of means having an intermittent movement in one direction only for forwarding a plurality of cigarettes from said source of supply, means in the path of movement of the forwarding means for removing said cigarettes from the forwarding means and for collocatively compressing said cigarettes while so removed and for replacing them in the forwarding means, and means for thereafter folding a sheet of wrapping material around the collocation of compressed cigarettes.
- 15 9. In a cigarette packing machine, the combination with a source of cigarette supply, of means for separating from the source of supply a definite number of cigarettes, means having an intermittent movement in one direction only for collectively forwarding the cigarettes so separated, means in the path of movement of the forwarding means for removing said cigarettes from the forwarding means and for collocatively compressing said cigarettes while so removed and for replacing them in the forwarding means, and means for thereafter folding a sheet of wrapping material around the collocation of compressed cigarettes.
- 20 10. In a cigarette packing machine, the combination with a source of cigarette supply, of means for separating from the source of supply a definite number of cigarettes, means having an intermittent movement in one direction only for collectively forwarding the cigarettes so separated, means in the path of movement of the forwarding means for removing said cigarettes from the forwarding means and for collocatively compressing said cigarettes while so removed and for replacing them in the forwarding means, means for thereafter folding a sheet of wrapping material around the collocation of compressed cigarettes, and means for inserting the wrapped collocation of cigarettes in a pouch.
- 25 11. In a cigarette packing machine, the combination with a source of cigarette supply, of means for separating from the source of supply a definite number of cigarettes, means for collectively forwarding the cigarettes so separated, means in the path of movement of the forwarding means for removing said cigarettes from the forwarding means and for collocatively compressing said cigarettes while so removed and for replacing them in the forwarding means, means for folding a sheet of wrapping material around the collocation of compressed cigarettes, and means for inserting the wrapped collocation of cigarettes in a pouch.
- 30 12. In a cigarette packing machine, the combination with a source of cigarette supply, of means for separating from the source of supply a definite number of cigarettes, means for collectively forwarding the cigarettes so separated, means in the path of movement of the forwarding means for removing said cigarettes from the forwarding means and for collocatively compressing said cigarettes while so removed and for replacing them in the forwarding means, means for removing and compressing means being spaced from the separating means a sufficient distance to enable an operator to remove from the forwarding means a defective cigarette and replace it with a perfect cigarette before the collection reaches the removing and compressing means, means for folding a sheet of wrapping material around the collocation of compressed cigarettes while so removed and for replacing them in the forwarding means.
- 35 13. In a cigarette packing machine, the combination with means having a step-by-step movement for forwarding a plurality of cigarettes, of means in the path of movement of the forwarding means and operative only while said forwarding means is at rest for removing said cigarettes from the forwarding means and for collocatively compressing said cigarettes while so removed and for replacing them in the forwarding means.
- 40 14. In a cigarette packing machine, the combination with a source of cigarette supply, of means having a step-by-step movement for forwarding a plurality of cigarettes from said source of supply, and means in the path of movement of the forwarding means and operative only while said forwarding means is at rest for removing said

cigarettes from the forwarding means and for collocatively compressing said cigarettes while so removed and for replacing them in the forwarding means.

- 5 15. In a cigarette packing machine, the combination with a source of cigarette supply, of means for separating from the source of supply a definite number of cigarettes, means having a step-by-step movement for
  - 10 10. collectively forwarding the cigarettes so separated, and means in the path of movement of the forwarding means and operative only while said forwarding means is at rest for removing said cigarettes from
  - 15 15. the forwarding means and for collocatively compressing said cigarettes while so removed and for replacing them in the forwarding means.

16. In a cigarette packing machine, the combination with a source of cigarette supply, of means for separating from the source of supply a definite number of cigarettes, means having a step-by-step movement for collectively forwarding the cigarettes so separated, means in the path of movement of the forwarding means and operative only while said forwarding means is at rest for removing said cigarettes from the forwarding means and for collocatively compressing said cigarettes while so removed and for replacing them in the forwarding means, the removing and compressing means being spaced from the separating means a sufficient distance to enable the operator to remove from the forwarding means any defective cigarette and replace it with a perfect cigarette before the collection reaches the removing means.

17. In a cigarette packing machine, the
40 combination with means having a step-by-
step movement for forwarding a plurality
of cigarettes, of means in the path of move-
ment of the forwarding means and oper-
ative only while said forwarding means is
45 at rest for removing said cigarettes from
the forwarding means and for collocatively
compressing said cigarettes while so re-
moved and for replacing them in the for-
warding means, and means for thereafter
50 folding a sheet of wrapping material
around the collocation of compressed ciga-
rettes.

18. In a cigarette packing machine, the combination with means having a step-by-step movement for forwarding a plurality of cigarettes, of means in the path of movement of the forwarding means and operative only while said forwarding means is at rest for removing said cigarettes from the forwarding means and for collocatively compressing said cigarettes while so removed and for replacing them in the forwarding means, and means for thereafter folding a sheet of wrapping material around the collocation of compressed ciga-

rettes while said collocation of compressed cigarettes is being advanced by the forwarding means.

19. In a cigarette packing machine, the combination with means having a step-by-step movement for forwarding a plurality of cigarettes, of means in the path of movement of the forwarding means and operative only while said forwarding means is at rest for removing said cigarettes from the forwarding means and for collocatively compressing said cigarettes while so removed and for replacing them in the forwarding means, means for folding a sheet of wrapping material around the collocation of compressed cigarettes, and means for inserting the wrapped collocation of cigarettes in a pouch. 70 75 80

20. In a cigarette packing machine, the combination with a source of cigarette supply, of means having a step-by-step movement for forwarding a plurality of cigarettes from said source of supply, means in the path of movement of the forwarding means and operative only while said forwarding means is at rest for removing said cigarettes from the forwarding means and for collocatively compressing said cigarettes while so removed and for replacing them in the forwarding means, and means for thereafter folding a sheet of wrapping material around the collocation of compressed cigarettes

21. In a cigarette packing machine, the combination with a source of cigarette supply, of means for separating from the source of supply a definite number of cigarettes, means having a step-by-step movement for collectively forwarding the cigarettes so separated, means in the path of movement 105 of the forwarding means and operative only while said forwarding means is at rest for removing said cigarettes from the forwarding means and for collocatively compressing said cigarettes while so removed and 110 for replacing them in the forwarding means, and means for thereafter folding a sheet of wrapping material around the collocation of compressed cigarettes.

22. In a cigarette packing machine, the 115
combination with a source of cigarette supply, of means for separating from the source of supply a definite number of cigarettes, means having a step-by-step movement for 120
collectively forwarding the cigarettes so separated, means in the path of movement of the forwarding means and operative only while said forwarding means is at rest for 125
removing said cigarettes from the forwarding means and for collocatively compressing said cigarettes while so removed and for replacing them in the forwarding means, means for thereafter folding a sheet of 130
wrapping material around the collocation of compressed cigarettes, and means for in- 135

serting the wrapped collocation of cigarettes in a pouch.

23. In a cigarette packing machine, the combination with a source of cigarette supply, of means for separating from the source of supply a definite number of cigarettes, means having a step-by-step movement for collectively forwarding the cigarettes so separated, means in the path of movement of the forwarding means and operative only while said forwarding means is at rest for removing said cigarettes from the forwarding means and for collocatively compressing said cigarettes while so removed and for replacing them in the forwarding means said removing and compressing means being spaced from the separating means a sufficient distance to enable an operator to remove from the forwarding means a defective cigarette and replace it with a perfect cigarette before the collection reaches the removing and compressing means, means for folding a sheet of wrapping material around the collocation of compressed cigarettes, and means for inserting the wrapped collocation of compressed cigarettes in a pouch.

24. In a cigarette packing machine, the combination with a source of cigarette supply, of means for separating from the source of supply a definite number of cigarettes, means having a step-by-step movement for collectively forwarding the cigarettes so separated, means in the path of movement of the forwarding means and operative only while said forwarding means is at rest for removing said cigarettes from the forwarding means and for collocatively compressing said cigarettes while so removed and for replacing them in the forwarding means said removing and compressing means being spaced from the separating means a sufficient distance to enable an operator to remove from the forwarding means a defective cigarette and replace it with a perfect cigarette before the collection reaches the removing and compressing means, means for folding a sheet of wrapping material around the collocation of compressed cigarettes while said collocation is being advanced by the forwarding means, and means for inserting the wrapped collocation of cigarettes in a pouch.

25. In a cigarette packing machine, the combination with means having a step-by-step movement for forwarding a plurality of cigarettes, of means in the path of movement of the forwarding means and operative only while said forwarding means is at rest for removing said cigarettes from the forwarding means and for collocatively compressing said cigarettes while so removed and for replacing them in the forwarding means, and means operative only when the forwarding means is at rest for folding a

sheet of wrapping material around the collocation of compressed cigarettes.

26. In a cigarette packing machine, the combination with means having a step-by-step movement for forwarding a plurality of cigarettes, of means in the path of movement of the forwarding means and operative only while said forwarding means is at rest for removing said cigarettes from the forwarding means and for collocatively compressing said cigarettes while so removed and for replacing them in the forwarding means, means operative only when the forwarding means is at rest for folding a sheet of wrapping material around the collocation of compressed cigarettes, and means for inserting the wrapped collocation of cigarettes in a pouch.

27. In a cigarette packing machine, the combination with means for forwarding a plurality of cigarettes resting upon a sheet of wrapping material, of means in the path of movement of the forwarding means for removing said cigarettes and wrapping material from the forwarding means and for collocatively compressing said cigarettes on the wrapping material while so removed and for replacing them in the forwarding means.

28. In a cigarette packing machine, the combination with a source of wrapping material supply, of means for forwarding a sheet of wrapping material from said source of supply, a source of cigarette supply, means for forwarding a plurality of cigarettes from said source of cigarette supply and resting upon the sheet of wrapping material, and means in the path of movement of the forwarding means for removing said cigarettes from the forwarding means and for collocatively compressing said cigarettes on the wrapping material while so removed and for replacing them in the forwarding means.

29. In a cigarette packing machine, the combination with a reel supporting a strip of wrapping material, of means for separating a sheet of wrapping material from the strip, a source of cigarette supply, means for separating a definite number of cigarettes from said source of cigarette supply and placing them upon the sheet of wrapping material, means for collectively forwarding the cigarettes so separated and placed, and means in the path of movement of the forwarding means for removing said cigarette from the forwarding means and for collocatively compressing said cigarettes on the wrapping material while so removed and for replacing them in the forwarding means.

30. In a cigarette packing machine, the combination with a reel supporting a strip of wrapping material, of means for separating a sheet of wrapping material from the

- strip, a source of cigarette supply, means for separating a definite number of cigarettes from said source of cigarette supply and placing them upon the sheet of wrapping material, means for collectively forwarding the cigarettes so separated and placed, means in the path of movement of the forwarding means for removing said cigarettes from the forwarding means and for collocatively compressing said cigarettes on the wrapping material while so removed and for replacing them in the forwarding means the removing and compressing means being spaced from the separating means a sufficient distance to enable the operator to remove from the forwarding means a defective cigarette and replace it with a perfect cigarette before the collection reaches the removing means.
- 20 31. In a cigarette packing machine, the combination with a reel supporting a strip of wrapping material, of means for separating a sheet of wrapping material from the strip, a source of cigarette supply, means for separating a definite number of cigarettes from said source of cigarette supply and placing them upon the sheet of wrapping material, means for collectively forwarding the cigarettes so separated and placed said means in the path of movement of the forwarding means for removing said cigarettes from the forwarding means and for collocatively compressing said cigarettes on the wrapping material while so removed and for replacing them in the forwarding means, and means for thereafter folding a sheet of wrapping material around the collocation of compressed cigarettes.
- 35 32. In a cigarette packing machine, the combination with a reel supporting a strip of wrapping material, of means for separating a sheet of wrapping material from the strip, a source of cigarette supply, means for separating a definite number of cigarettes from said source of cigarette supply and placing them upon the sheet of wrapping material, means for collectively forwarding the cigarettes so separated and placed, means in the path of movement of the forwarding means for removing said cigarettes from the forwarding means and for collocatively compressing said cigarettes while so removed and for replacing them in the forwarding means, and means for thereafter folding the sheet of wrapping material around the collocation of compressed cigarettes while said collocation of compressed cigarettes is being advanced by the forwarding means.
- 40 33. In a cigarette packing machine, the combination with a reel supporting a strip of wrapping material, of means for separating a sheet of wrapping material from the strip, a source of cigarette supply, means for rating a definite number of cigarettes from said source of cigarette supply and placing them upon the sheet of wrapping material, means for collectively forwarding the cigarettes so separated and placed, means in the path of movement of the forwarding means for removing said cigarettes from the forwarding means and for collocatively compressing said cigarettes on the wrapping material while so removed and for replacing them in the forwarding means the removing and compressing means being spaced from the separating means a sufficient distance to enable the operator to remove from the forwarding means any defective cigarette and replace it with a perfect cigarette before the collection reaches the removing means.
- 45 34. In a cigarette packing machine, the combination with a reel supporting a strip of wrapping material, of means for separating a sheet of wrapping material from the strip, a source of cigarette supply, means for separating a definite number of cigarettes from said source of cigarette supply and placing them upon the sheet of wrapping material, means for collectively forwarding the cigarettes so separated and placed said forwarding means having a step-by-step movement, means in the path of movement of the forwarding means and operative only while said forwarding means is at rest for removing said cigarettes from the forwarding means and for collocatively compressing said cigarettes on the wrapping material while so removed and means for replacing them in the forwarding means.
- 50 35. In a cigarette packing machine, the combination with a reel supporting a strip of wrapping material, of means for separating a sheet of wrapping material from the strip, a source of cigarette supply, means for separating a definite number of cigarettes from said source of cigarette supply and placing them upon the sheet of wrapping material, means for collectively forwarding the cigarettes so separated and placed said forwarding means having a step-by-step movement, means in the path of movement of the forwarding means and operative only while said forwarding means is at rest for removing said cigarettes from the forwarding means and for collocatively compressing said cigarettes on the wrapping material while so removed and for replacing them in the forwarding means, the removing and compressing means being spaced from the separating means a sufficient distance to enable the operator to remove from the forwarding means any defective cigarette and replace it with a perfect cigarette before the collection reaches the removing means.
- 55 36. In a cigarette packing machine, the combination with a reel supporting a strip of wrapping material, of means for separating a sheet of wrapping material from the strip, a source of cigarette supply, means for

separating a definite number of cigarettes from said source of cigarette supply and placing them upon the sheet of wrapping material, means for collectively forwarding the cigarettes so separated and placed said forwarding means having a step-by-step movement, means in the path of movement of the forwarding means and operative only while said forwarding means is at rest for 5 removing said cigarettes from the forwarding means and for collocatively compressing said cigarettes on the wrapping material while so removed and for replacing them in the forwarding means, and means for thereafter 10 folding a sheet of wrapping material around the collocation of compressed cigarettes. 15

37. In a cigarette packing machine, the combination with a reel supporting a strip 20 of wrapping material, of means for separating a sheet of wrapping material from the strip, a source of cigarette supply, means for separating a definite number of cigarettes from said source of cigarette supply and 25 placing them upon the sheet of wrapping material, means for collectively forwarding the cigarettes so separated and placed said forwarding means having a step-by-step movement, means in the path of movement 30 of the forwarding means and operative only while said forwarding means is at rest for removing said cigarettes from the forwarding means and for collocatively compressing said cigarettes on the wrapping material 35 while so removed and for replacing them in the forwarding means, means for holding the sheet of wrapping material around the collocation of compressed cigarettes, and means for inserting the wrapped collocation 40 of cigarettes in a pouch.

38. In a cigarette packing machine, the combination with a source of cigarette supply, of means for separating a definite number of cigarettes from the source of supply, 45 means having an intermittent movement in one direction only for forwarding the cigarettes so separated, means for compressing the cigarettes so separated, and means for folding a sheet of wrapping material around the cigarettes after they are compressed. 50

39. In a cigarette packing machine, the combination with a source of cigarette supply, of means for separating a definite number of cigarettes from the source of supply, 55 means having an intermittent movement in one direction only for forwarding the cigarettes so separated, means for compressing the cigarettes so separated, means for folding a sheet of wrapping material around the cigarettes after they are compressed, and means for inserting the wrapped cigarettes in a pouch. 60

40. In a cigarette packing machine, the 65 combination with a source of wrapping ma-

terial supply, of means for separating a sheet of wrapping material from said source of supply, a source of cigarette supply, a device for separating a definite number of cigarettes from said source of cigarette supply and placing them upon the sheet of wrapping material, means for compressing the cigarettes so separated and placed, and means for folding the sheet of wrapping material around the cigarettes after they are compressed. 70 75

41. In a cigarette packing machine, the combination with a source of wrapping material supply, of means for separating a sheet of wrapping material from said source of supply, a source of cigarette supply, 80 means for separating a definite number of cigarettes from said source of cigarette supply and placing them upon the sheet of wrapping material, means for compressing the cigarettes so separated and placed, means for folding the sheet of wrapping material around the cigarettes after they are compressed, and means for inserting the wrapped cigarettes in a pouch. 85 90

42. In a cigarette packing machine, the combination with a reel supporting a strip of wrapping material, of means for separating a sheet of wrapping material from the strip, a source of cigarette supply, a device 95 for separating a definite number of cigarettes from the source of cigarette supply and placing them upon the sheet of wrapping material, means for compressing the cigarettes so separated, and means for folding 100 the sheet of wrapping material around the cigarettes after they are compressed. 105

43. In a cigarette packing machine, the combination with a reel supporting a strip 110 of wrapping material, of means for separating a sheet of wrapping material from the strip, a source of cigarette supply, means for separating a definite number of cigarettes from said source of cigarette supply and placing them upon the sheet of wrapping material, means for compressing the cigarettes so separated and placed, means for folding a sheet of wrapping material around the cigarettes after they are compressed, and means for inserting the 115 wrapped cigarettes in a pouch. 120

44. In a cigarette packing machine, the combination with a rotating turret provided with a pocket adapted to hold and forward a plurality of cigarettes, of means in the 120 path of movement of the turret for removing said cigarettes from the turret pocket and for collocatively compressing said cigarettes while so removed and for placing them in the pocket. 125

45. In a cigarette packing machine, the combination with a rotating turret provided with a pocket adapted to hold and forward a plurality of cigarettes, of means in the 130 path of movement of the turret for remov-

ing said cigarettes from the turret pocket and for collocatively compressing said cigarettes while so removed and for replacing them in the pocket, and means coöperating with the turret for thereafter folding a sheet of wrapping material around the collocation of cigarettes.

46. In a cigarette packing machine, the combination with a rotating turret provided with a pocket adapted to hold and forward a plurality of cigarettes, of means in the path of movement of the turret for removing said cigarettes from the pocket and for collocatively compressing said cigarettes while so removed and for replacing them in the pocket, means coöperating with the turret for thereafter folding a sheet of wrapping material around the collocation of cigarettes, and means for inserting the wrapped collocation of cigarettes in a pouch.

47. In a cigarette packing machine, the combination with a turret having a step-by-step movement and provided with a pocket adapted to hold and forward a plurality of cigarettes, of means in the path of movement of the turret and operative only while said turret is at rest for removing said cigarettes from the turret pocket and for collocatively compressing said cigarettes while so removed and for replacing them in the turret pocket.

48. In a cigarette packing machine, the combination with a turret having a step-by-step movement and provided with a pocket adapted to hold and forward a plurality of cigarettes, of means in the path of movement of the turret and operative only while said turret is at rest for removing said cigarettes from the turret pocket and for collocatively compressing said cigarettes while so removed and for replacing them in the turret pocket, and means coöperating with the turret and operative only while said turret is at rest for folding a sheet of wrapping material around the compressed collocation of cigarettes.

49. In a cigarette packing machine, the combination with a turret having a step-by-step movement and provided with a pocket adapted to hold and forward a plurality of cigarettes, of means in the path of movement of the turret and operative only while said turret is at rest for removing said cigarettes from the turret pocket and for collocatively compressing said cigarettes while so removed and for replacing them in the turret pocket, means coöperating with the turret and operative only while the turret is at rest for folding a sheet of wrapping material around the compressed collocation of cigarettes, and means for inserting the wrapped collocation of cigarettes in a pouch.

50. In a cigarette packing machine, the combination with a turret having a step-by-

step movement and provided with a pocket adapted for holding and forwarding a plurality of cigarettes, of means in the path of movement of the turret and operative only when said turret is at rest for removing said cigarettes from the turret pocket and for collocatively compressing said cigarettes while so removed and for replacing them in the turret pocket, reciprocating blades co-operating with the pocket for folding a sheet of wrapping material around the collocation of compressed cigarettes, and means for inserting the wrapped collocation of cigarettes in a pouch.

51. In a cigarette packing machine, the combination with means for forwarding a plurality of cigarettes, of means in the path of movement of the forwarding means for removing said cigarettes from the forwarding means and for collocatively compressing said cigarettes while so removed and for replacing them in the forwarding means, means associated with the removing means for assembling a card with the cigarettes just prior to the compressing action, and means for folding a sheet of wrapping material around the compressed collocation of cigarettes and the card.

52. In a cigarette packing machine, the combination with means for forwarding a plurality of cigarettes, of means in the path of movement of the forwarding means for removing said cigarettes from the forwarding means and for collocatively compressing said cigarettes while so removed and for replacing them in the forwarding means, means associated with the removing means for assembling a card with the cigarettes just prior to the compressing action, means for folding a sheet of wrapping material around the compressed collocation of cigarettes and the card, and means for inserting the wrapped cigarettes in a pouch.

53. In a cigarette packing machine, the combination with forwarding means, of a pocket carried by the forwarding means and adapted to support a plurality of cigarettes, a movable bottom for the pocket, frictional devices for retaining said bottom in position, a pair of swingable arms adapted to aline the cigarettes in the pocket, toggle mechanism for holding said arms either in open or closed position, and means for operating said arms against the action of the toggle mechanism.

54. In a cigarette packing machine, the combination with forwarding means, of a pocket carried by the forwarding means and adapted to support a plurality of cigarettes, a two-part movable bottom for the pocket, independently acting frictional devices for independently retaining the two parts of the bottom in position, a pair of swingable arms adapted to aline the cigarettes in the pocket, toggle mechanism for holding said arms

either in open or closed position, and means for operating said arms against the action of the toggle mechanism.

55. In a cigarette packing machine, the combination with a rotating turret having a pocket adapted to hold and forward a plurality of cigarettes, a compressing mechanism in the path of movement of the turret pocket, means for transferring the cigarettes from the turret pocket to the compressing mechanism, means for reducing the size of the turret pocket after the cigarettes have been removed therefrom, and means for retransferring the compressed cigarettes to the reduced turret pocket.

56. In a cigarette packing machine, the combination with a rotating turret provided with a pocket for holding and forwarding a plurality of cigarettes, compressing mechanism located in the path of movement of the turret pocket and including a pocket having a movable top and one movable side and operating connections, means for transferring the cigarettes to the pocket of the compressing mechanism, means for reducing the size of the turret pocket after the cigarettes have been transferred to the pocket of the com-

pressing mechanism, and means for replacing the compressed cigarettes in the reduced turret pocket.

57. In a cigarette packing machine, the combination with a turret provided with a pocket for holding and forwarding a collocation of compressed cigarettes resting upon a sheet of wrapping material, reciprocating folding devices coöperating with the turret pocket for partially folding the sheet of wrapping material around the collocation of cigarettes, mechanism for transferring the partially wrapped collocation of cigarettes from the turret pocket, stationary folding devices coöperating with the transferring mechanism to effect the final fold of the sheet of wrapping material around the collocation of cigarettes, and means for inserting the completely wrapped collocation of cigarettes in a pouch.

In testimony whereof, I have signed my name to this specification in the presence of two subscribing witnesses.

ELBERON D. SMITH.

Witnesses:

SYDNEY I. PRESCOTT,
ELIZABETH LOUISE RUSSELL.
